UNITED STATES PATENT OFFICE

MALVERN W. SEVERANCE, OF CLEVELAND, OHIO, ASSIGNOR TO WILLARD STORAGE BATTERY COMPANY, OF CLEVELAND, OHIO, A CORPORATION OF WEST VIRGINIA

BATTERY HANDLE

Application filed June 24, 1930, Serial No. 463,390. Renewed May 31, 1932.

This invention relates to battery handles, and more particularly to a device of this character adapted to be secured to an electric storage battery container having a handle to increase the purchase provided by the handheld and facilitate the handling of heavier batteries.

A battery handle of this character is described and claimed in my copending application Serial No. 430,149, filed February 21, 1930, and the present invention may be considered as an improvement thereon.

It is an object of the present invention to provide a battery handle which may be quickly and simply attached to a battery container without in any way penetrating or otherwise marring the container.

A further object is to provide means for maintaining the handle parts in engagement with the container parts under pressure.

Another object is to simplify and improve the means for securing the handle parts together.

Other objects and features of novelty will be apparent as the following description proceeds, reference being had to the accompanying drawing, in which

Figure 1 is an elevation of a portion of a battery container showing one embodiment of the present invention applied thereto.

Fig. 2 is a section through the battery container showing the handheld to which the handle according to the present invention is to be applied.

Fig. 3 is a section taken along the line 3—3 of Fig. 1.

Fig. 4 is an elevation of the main handle plate.

Fig. 5 is a section along the line 5—5 of Fig. 4.

Fig. 6 is an elevation of the smaller handle member.

Fig. 7 is a section along the line 7—7 of Fig. 6.

Fig. 8 is an elevation of a modified handle embodying certain features of the present invention.

Fig. 9 is a section along the line 9—9 of Fig. 8.

Fig. 10 is an elevation of the main handle plate of the form shown in Fig. 8.

Fig. 11 is a section along the line 11—11 of Fig. 10.

Fig. 12 is an elevation of the smaller handle plate of the type shown in Fig. 8; and

Fig. 13 is a section along the line 13—13 of Fig. 12.

Referring more particularly to the drawing, Fig. 1 shows a portion of a battery container 10, preferably of bituminous material, rubber, or other composition, and molded or otherwise formed so as to provide a marginal reinforcement 11 at the upper edge of the container, and a handheld including a shoulder 12 formed beneath the portion 11 by a recess undercut sufficiently to receive the fingers of a workman for handling the battery container. In the form shown, the container is provided with stub handles 11^a which are formed integral with the end walls and project above the top of the container. While the handheld is adequate for handling with certain types of batteries, it is inadequate for other purposes, as set forth in detail in my copending application hereinbefore referred to. According to the present invention, a handle is provided which may be very readily attached to the container and provides a more adequate grip for the hand of the workman, to facilitate the handling of larger and heavier batteries. This handle, when attached, is constructed to cooperate with the battery hold-down, and is otherwise well adapted for the purposes set forth.

In the preferred embodiment of the invention illustrated in Figs. 1 to 7 inclusive, a main handle member is provided as shown in Figs. 4 and 5 and comprises a body portion 13 which may be formed of a sheet metal plate and constructed in the form shown by a single stamping operation. A hand aperture 14 is formed in the upper portion of the plate 13, leaving side arms 15 at each side thereof, and a hand grip portion 16 is formed above the aperture 14. The grip 16 is preferably formed by a flange 17 rolled up from metal struck out to form the aperture 14, and an upper flange 18 which is bent laterally, so

that the edges of the flanges 17 and 18 come together and form a substantially tubular hand grip portion.

Integral with the bottom of the plate 13 are a pair of flanges 19 which are adapted to underlie the shoulder 12 and take the weight of the battery when the hand grip 16 is lifted. A flange 20 is struck up from the mid-portion of the plate 13, preferably at an angle, forming a slot 21 in the plate 13. The flange 20 is folded to provide a depending lip 22.

For securing the member 13 on the end wall, a cooperating plate 23 is provided, as shown in Figs. 6 and 7. The plate 23 has a laterally extending flange 24 which is further provided with a depending lip 25, and depressed as at 26' to receive the battery hold-down. The mid-portion of the plate 23 has a flange 26 struck up therefrom forming a slot 27. The flange 26 is preferably disposed at an angle inclined oppositely to the angle of the flange 20. The flange 26 is further deformed to provide an upstanding lip 28.

To apply the handle parts as described to the end wall of the battery container 10, the plate 13 is placed against the side of the end wall with the flanges 19 underlying the shoulder 12. The flange 24 is then inserted through the hand aperture 14, so as to overlie the top of the container or the stub handles, with the lip 25 depending inside the same. In this operation, the flange 20 will project through the slot 27, so that the lips 22 and 28 will come into alignment. A wedge 29 is then inserted between the flanges 20 and 26 and underlying the lips 22 and 28. It will be obvious that the action of the wedge 29 will urge the flange 24 and rim 25 toward the flanges 19 and thus grip the portion of the end wall therebetween under pressure. It will also be noted that the application of the handle to the battery container, as described, will not penetrate or otherwise mar the surface of the battery container.

45 A modified form of the invention is illustrated in Figs. 8 to 13 inclusive. In this form the main handle plate member as shown in Figs. 10 and 11 comprises a body portion 30, which is adapted to cooperate with the smaller plate illustrated in Figs. 12 and 13. Portions of these members which are identical with those described in connection with the preferred embodiment are given the same reference characters and will not be described in detail. A flange 31 is struck up from the body portion 30 forming a slot 32. The flange 31 projects laterally and is preferably parallel to the hand grip 16. The smaller plate 33 has a flange 34 struck up therefrom leaving a slot 35. The flange 34 is preferably parallel to the flange 31 when the plates are fitted together in the manner hereinbefore described. The flange 31 is slightly longer than the flange 34 so that when the plate 33 is applied to the member 30, the flange 31 pro-

jecting through the slot 35 will be in alignment with the flange 34. The flange 34 is provided with apertures 36 adapted to receive machine screws 37, and the flange 31 is upset and threaded to provide bosses 38, which receive the screws 37. When interfitted, as shown in Figs. 8 and 9, to mount the modified handle on the container, it is obvious that tightening of the screws 37 will securely grip the portion of the end wall between the flange 24 and rim 25 and the flanges 19.

While these embodiments of the invention have been illustrated and described in such detail as to enable any one skilled in the art to practice the invention, nevertheless, it is to be understood that the invention is not limited to any of the details disclosed, other than necessitated by the development of the prior art; but instead it is to be understood that the invention embraces such embodiments of the broad idea as fall within the scope of the subjoined claims.

Having thus described my invention, I claim:

1. A container handle comprising a pair of sheet metal members having cooperating portions adapted to receive a portion of a container therebetween, one of said members having a slot therein and an inclined flange adjacent thereto formed by the metal struck up to form said slot, and the other of said members having an abutment projecting through said slot, and a wedge engaging said inclined flange and abutment for urging said cooperating portions toward each other.

2. In a handle for a storage battery box, a pair of cooperating sheet metal members, one of said members having a hand-hold portion, a flat body portion adapted to engage the end wall of the battery box and a hook adapted to engage a shoulder in the end wall of the battery box, said body portion having an outturned flange, the second sheet metal member having a portion adapted to hook over the top of the end wall, and a flat body portion provided with an aperture through which said flange extends, said members slidably engaging each other, said second member having a flange adjacent said aperture, and means acting upon said flanges for drawing said hooks toward each other.

3. In combination with a storage battery box having stub handles on the end walls thereof, a handle comprising a pair of cooperating sheet metal members, one of said members having a hand-hold portion, a flat body portion adapted to engage the end wall of the battery box and a hook adapted to engage a shoulder in the end wall of the battery box, said body portion having an outturned flange, the second sheet metal member having a portion adapted to hook over the top of the stub handle, and a flat body portion provided with an aperture through

which said flange extends, said members slidably engaging each other, said second member having a flange adjacent said aperture, and means acting upon said flanges for drawing said hooks toward each other.

4. In a handle for a storage battery box, a pair of cooperating sheet metal members, one of said members having a hand-hold portion, a flat body portion adapted to engage 10 the end wall of the battery box and a hook adapted to engage a shoulder in the end wall of the battery box, said body portion having an outturned flange, the second sheet metal member having a portion adapted to hook 15 over the top of the end wall, and a flat body portion provided with an aperture through which said flange extends, said members slidably engaging each other, said second member having a flange adjacent said aperture, and a screw acting upon said flanges for drawing said hooks toward each other.

In testimony whereof, I hereunto affix my signature.

MALVERN W. SEVERANCE.
